UNITED STATES PATENT OFFICE.

FERDINAND W. KROGH, OF SAN FRANCISCO, CALIFORNIA.

BALANCING MEANS FOR CENTRIFUGAL PUMPS.

1,146,078.

Specification of Letters Patent. Patented July 13, 1915.

Application filed January 8, 1913. Serial No. 740,299.

To all whom it may concern:

Be it known that I, FERDINAND W. KROGH, of San Francisco, California, have invented certain new and useful Improvements in Balancing Means for Centrifugal Pumps, whereof the following is a specification.

My invention relates to the art of pumping from deep or shallow wells, and especially to centrifugal pumps adapted for such operation. The weight of the long shaft and the large impeller used in such installations, bears with injurious force on the step bearing or supporting shoulder located at the bottom of the well, and various devices for counteracting the downward thrust of the moving parts so as to give them a liquid bearing instead of a solid one, have been devised.

My invention has for its object to provide in centrifugal pumping devices of the kind referred to, new and improved means for providing a liquid bearing for the bottom of the moving parts, in which said moving parts shall float.

With this object in view, my invention consists in new and improved means for converting the energy of the water discharged from the impeller into an upward thrust counteracting the downward thrust of the moving parts, and in new and improved means for adjusting the two opposing thrusts so that the moving parts of my apparatus will float in a liquid bearing.

I accomplish my object by the means set forth in the following specification, particularly pointed out in the claims at the end hereof, and illustrated in the accompanying two sheets of drawing, in which,

Figure 1 is a vertical section of a centrifugal pump showing my invention in position thereon, Fig. 2 is a top plan view of the impeller; and Fig. 3 is an inverted view of the upper part of the casing of the pump.

The same symbol of reference marks the same part in whichever view said part may appear.

Describing now my invention in detail, 1 is a pump casing of a deep well pumping installation A, of which B is the suction pipe, C the rotary shaft, and D, the impeller. The casing, with reference to the construction and operation of my invention may be conceived to be divided into an upper chamber 2, and a lower chamber 3, by the impeller D which draws water from the

suction pipe B and discharges it to the surface through the discharge pipe E from the space 4. Energy is imparted to the discharged water by the impeller as it leaves the impeller outlets, so that the water in the space 4 is under a pressure proportional to the power of the pump.

The space 4 communicates with the lower chamber 3 of the casing 1, and the energy of the discharged water is therefore distributed underneath the impeller as the water from space 4 flows into chamber 3. An upward thrust is thereby given to the impeller, its shaft and whatever other parts may be attached to said impeller and shaft, which is measured by the area of the under surface of the impeller and the energy of the discharged water. Hence results a lifting action on the moving parts which takes them off their solid stepbearing or supporting shoulder. But the said lifting action tends to thrust the moving parts into engagement with the upper part of the casing, forming an oppositely disposed solid bearing, which it is very desirable to eliminate. I accomplish the desired result by forming the upper chamber 2 of the casing 1 into two parts *a* and *b*, by the flanged ring 5 on the impeller, and by conforming the casing as at *a* to correspond with the form of said ring, leaving a leakage passage 6 between the parts *a* and *b*.

While the part *b* of the upper chamber communicates with the space 4, and therefore allows the energy of the discharged water to act downwardly against the impeller, and in opposition to the energy from the same source acting on the bottom of the impeller, the downward energy so imparted is less than the upward energy, because the surface over which it is distributed is less, being measured by the area of the bottom of the part *b* only of chamber 2.

From the part *a* of chamber 2 a relief port or ports 7 are provided, which communicate with the discharge relief pipes 8 opening into the air or into the suction pipe B below. Boses 9 are provided inside the casing 1 around the ends of pipes 8, so that when the impeller is in its topmost position, as that shown in Fig. 1 it will not interfere materially with the leakage from part *b* into part *a* of chamber 2, which leakage is caused by the energy of the water discharged from the impeller and tend to continue until the water in part *a* of chamber 2 is sufficient to

overcome the pressure from below. The pressure in part *a* is allowed to rise because the relief ports 7 are closed by the flanged ring 5 on impeller D, whenever the impeller 5 is raised high enough to make a moving contact between the bosses and the flanged ring. But as soon as the pressure of water in part *a* becomes great enough to offset, with the co-operation of the energy in part *b*, the upward energy in chamber 3, then the weight of the moving parts tends to carry them downwardly again, and the relief ports 7 are opened. Enough water escapes from the part *a* of chamber 2 to reduce the pressure 10 in that part to a point where the upward-thrust is greater than the downward thrust; whereupon the moving parts are lifted again off shoulder 10. The described reactions continue until the impeller occupies a position wherein the escape from the relief pipes just equals the leakage through passage 6. In that position the impeller is floating in the water, the liquid stepbearing has been formed, and contact with solid bearings 15 has been eliminated.

I do not depend on vacua above my impeller to produce the results aimed at, because sometimes the water in the wells lies wholly below the pump and sometimes covers the pump completely. But as will be seen by the above description I rely wholly on the positive upward action of the energy of the water discharged from the impeller to lift and its positive action upward and 30 downward to balance the moving parts of my pump...

Having thus described my invention and believing I have produced useful and novel improvements in the art to which it appertains let it be understood that I do not wish to be limited to the exact construction and arrangement of the several parts composing the same as many changes can be made without departing from the spirit thereof but—

45 What I claim and desire to secure by United States Letters Patent is:—

1. In a centrifugal pumping device, the combination with a casing provided with a relief port opposite the intake, an impeller 50 provided with a chamber communicating with said port, and an annular flange projecting inwardly from the outer edge of said chamber adapted to close or open said port.

2. In a centrifugal pump, a casing provided with a chamber opposite the intake, having a relief port, an impeller provided with a chamber operating in the casing chamber and provided with an upper inner projecting flange adapted to close or open 55 said relief port.

3. In a centrifugal pump, a casing provided with a chamber and a relief port, an

impeller provided with a chamber having an inner projecting flange adapted to close said relief port, a boss between said relief port and said projecting flange for allowing the water passing between the stationary and running parts to freely circulate within the inner chamber.

4. In a centrifugal pumping device, the combination with an impeller, of a casing having a space into which the water from the impeller is discharged, a lower chamber communicating with said space, an upper chamber and a relief port from said upper chamber, a ring carried upon the upper face of the impeller and adapted by its conformation and that of the casing to divide said upper chamber into two parts, leaving a leakage passage therebetween, one of said parts communicating with said space and the other part communicating with said relief port, said relief port being controlled by a transversely extending surface on said ring.

5. A centrifugal pump comprising an impeller and a casing having a space for water discharging from said pump and an upper and lower chamber communicating with said space, a flanged ring having a rectangular inner projecting edge constructed on said impeller and co-acting with the casing to partially shut off part of the upper surface of said impeller from said space and a relief port in the region inclosed by said ring controlled by said inner projecting edge.

6. A centrifugal pump comprising a casing having a discharge outlet and a suction inlet, said casing having a relief passage one end of which is in communication with the suction inlet side of the casing and the other end is in communication with the side of the casing opposite its suction inlet side, a runner within the casing having on its suction inlet side a running slip joint with the suction inlet of the casing, and having on its opposite side an annular angled flange, one portion of which forms a running slip joint with the casing on its side opposite its suction inlet side and the other portion of which is adapted by its approach to and its recession from the communication of the relief passage with said opposite side of the casing, to throttle and open said communication; and a longitudinal slidable driving shaft carrying said runner.

In testimony that I claim the foregoing I have hereto set my hand this 9th day of December, 1912, in the presence of witnesses.

FERDINAND W. KROGH.
